UNITED STATES PATENT OFFICE.

NICHOLAS KOPP, OF PITTSBURGH, PENNSYLVANIA.

DESIGN FOR A SHADE.

47,335.

Specification for Design.

Patented May 11, 1915.

Application filed February 9, 1915. Serial No. 7,131. Term of patent 3½ years.

To all whom it may concern:

Be it known that I, NICHOLAS KOPP, a citizen of the United States, residing at Pittsburgh, in the county of Allegheny and State of Pennsylvania, have invented a new, original, and ornamental Design for a Shade, of which the following is a specification, reference being had to the accompanying drawing, forming part thereof.

The figure is a side elevation of a shade showing my new design.

I claim:—

The ornamental design for a shade as shown.

NICHOLAS KOPP.

Witnesses:

S. A. McFARLAND,
W. G. DOOLITTLE.
